GEORG VON ARCO AND ALEXANDER MEISSNER, OF BERLIN, GERMANY.

CONNECTION FOR ELECTRIC RELAYS WORKING WITH IONIZED GAS-GAP

1,314,102.

Specification of Letters Patent. Patented Aug. 26, 1919.

Application filed January 10, 1914, Serial No. 811,366. Renewed July 1, 1918. Serial No. 242,891.

To all whom it may concern:

Be it known that we, GEORG VON ARCO and ALEXANDER MEISSNER, citizens of the Empire of Germany and the Empire of 5 Austria, respectively, and residing at Berlin, Germany, have invented certain new and useful Improvements in Connections for Electric Relays Working with Ionized Gas-Gap, of which the following is a specification.

Our present invention relates to electric relays, particularly to those having an ionized gap, the preferred form consisting of a glass vessel partially evacuated or filled with 15 gas at low pressure and which contains a heated cathode and one or more anodes. The rays emitted by the heated cathode are supposed to ionize the gas so that a permanent path of current is established through 20 the relay. The currents reinforced by the relay are supplied to a circuit containing the heated cathode and an auxiliary anode, and strengthened currents thus occur in the circuit containing the cathode and the main 25 anode, increased current being thus obtained from the source of current which supplies the circuit through the main anode.

In another form the well-known Braun tube is employed, and the oscillations to 30 be strengthened are supplied to special electrodes between which is led the current of ions which passes from the cathode to the anode.

As the operating part of relays of this 35 character does not possess mass, they are particularly adapted to alternating currents of high frequency in which exact reproduction of changes is important; for example, for special microphone currents and producing strengthened repeated oscillations for 40 wireless telegraphy and telephony.

In this specification we show connections of circuits which may co-act with the relay to obtain the reinforced effect desired; some 45 of these particularly relate to the secondary circuit of the relay, *i. e.*, that to which the reinforced relay currents are supplied, being interconnected with the circuit connected to the primary circuit of the relay 50 and which carries the current to be strengthened, so that the energy supplied by the relay passes through the relay the second time; and our invention relates particularly to this re-coupling between the circuits, constituting a means for reinforcing the effect 55

of the relay so that very weak currents may readily be strengthened until they are entirely perceptible; this introduces, as we believe, an entirely new mode of operation. For example, if an electric oscillating system is connected with the relay in the desired manner, it is possible to maintain permanent oscillations in the system, which is of great importance in wireless telegraphy and telephony, as this makes it possible for 60 the first time, so far as we are advised, to produce undamped oscillations of absolutely 65 constant amplitude.

Furthermore, our invention enables specially effective receiving connections to 70 be made by causing the relay to act as a receiving arrangement in a common detector or indicator circuit.

If the oscillations produced by the relay are tuned in well-known ways to a frequency 75 which differs slightly from the received oscillations, then by means of the ordinary receiving apparatus undamped oscillations in the form of perfectly pure tones can be received, which are caused by the interference of the two oscillations. Owing to the reinforcing which is possible by our invention we can receive oscillations of very low intensity, such as could not be made perceptible by other means, and consequently 80 can increase the range of wireless communications.

In the drawings hereto annexed, which show diagrammatically several embodiments 85 of the invention,

Fig. 1 is a diagram showing the general principle.

Fig. 2 shows an application to a wireless receiving system having an indicating instrument connected in circuit.

Fig. 3 shows a similar application in which the indicator is connected directly with the secondary coil of the antenna.

Fig. 4 shows a construction in which a separate detector is omitted.

Fig. 5 shows an analogous system to Fig. 4, having the primary of the telephone transformer in parallel to the re-coupling coil.

Figs. 6 and 7 show additional forms of circuits adapted to the heterodyne or beat method of operation.

Referring first to Fig. 1, the relay comprises a glass vessel 1 containing three electrodes 2, 3 and 4, of which 2 designates the 110

heated cathode, preferably a metal filament; the cathode is heated by the battery 5 and emits electrons. The anode 3 generally consists of a wire spiral, and an auxiliary anode 4 is usually a metal grid shutting off more or less the space between the anode and the cathode; while the space between the electrodes 2 and 4 constitutes the primary circuit or gap a , and the space between the electrodes 2 and 3 is the secondary gap b of the relay. The currents to be reinforced are supplied to the relay over a circuit 7 from the circuit 6, which may be a long distance telephone line or the circuit of a wireless telegraph receiving arrangement.

The circuit 6 is coupled with the coil 8 of the circuit 7 in a suitable way, and the circuit 7 is connected both with the cathode 2 and the auxiliary anode 4. The reinforced currents occur in the circuit 9, which is connected to the cathode 2 and the anode 3 and contains a source of energy 10; for example, a direct current dynamo or a battery. The strengthened oscillations are conducted from the circuit 9 to the coil 11 and thence to a telephone or detector in the circuit.

According to our invention, we connect the circuit 9 by a second linking with the circuit 7; this may be effected by means of the coil 12 connected in the circuit 9 and inductively coupled with the coil 8 of circuit 7; alternative methods of connecting are those by capacity effect or galvanically, or a similar coupling may be had with circuit 6, as will be apparent. Due to this re-coupling a portion of the strengthened energy of the circuit 9 is supplied to the relay and is again reinforced until by this cumulative action a state of equilibrium is obtained. The coupling between the coil 12 and the coil 8 is preferably made adjustable; by regulating this, the maximum degree of reinforcement can be readily obtained.

Fig. 2 shows how the connection can be used as a receiving arrangement in wireless telegraphy. The oscillations received by the aerial circuit 13 pass to the relay 50 from the coupling coil 14, and this forms an inductive coupling of the coil 8 and circuit 7 to the aerial. The reinforced high frequency oscillations can then be supplied to a closed circuit 15, containing an adjustable condenser 17 connected inductively to circuit 9 by the coils 11, 16. The circuit 15 also contains a reinforcing coil 12 by which it is coupled inductively to the circuit 7 at 8^a, this being preferably an adjustable coupling, as indicated. The reinforced energy is supplied again to the relay, as above. The aerial 13 has a tuning condenser 18; and a detector circuit containing a desired form of detector 19 and condenser 20,

branches from the coil 16 of the circuit 15, to which it is adjustably connected as shown, the telephone 21 being in parallel with the condenser 20.

In the arrangement so far described, the detector circuit or the indicator 21 is connected with the circuit to which the strengthened currents are supplied by the relay.

In Fig. 3, however, we show a receiving connection for wireless telegraphy in which the indicating instrument or detector circuit is connected directly with the secondary antenna coupling coil. In this arrangement the currents to be reinforced are transmitted by the aerial 13 through coils 14, 16 to the circuit 15 and are supplied to the primary circuit 7 of the reinforcing relay from the coil 8. The circuit 9 which carries the reinforcing currents is re-coupled by coil 12 with circuit 15. The detector circuit 19, 20, 21 is directly connected to the circuit 15, as before. The advantage of this connection is that the reinforced apparatus can be connected directly to well-known forms of receiving connection.

It is, of course, well known that cathode ray tubes of the general kind described above may be employed as detectors in wireless communication, and in Fig. 4 we show how the detector 19 of Fig. 2, etc., can be dispensed with and the relay can be used as a detector with the described re-coupling, the indicating instrument being directly connected to the circuit carrying the reinforced relay currents. The relay connected as described above contains a coil 8 for coupling circuit 7 with the aerial and its coil 14. The secondary relay circuit 9 is re-coupled by the coil 12 with the circuit 7; but this circuit contains also the primary winding 26 of the telephone transformer, to the secondary winding 27 of which the telephone 21 is connected, and an adjustable condenser 28 is connected in parallel with the primary winding 26; of course, the telephone 21 could be connected directly instead of inductively to the circuit 9, as is well understood.

In Fig. 5 we show how the coil 26 of the telephone transformer and the re-coupling coil 12 may be connected in parallel instead of in series, as is the arrangement in Fig. 4.

In both Figs. 4 and 5 the high frequency currents received from the aerial are reinforced by the relay 1 and are transformed into audio-frequency currents. The secondary currents being repeatedly led into the primary circuit the audio-frequency component is rapidly increased; so that the reinforced audio-frequency currents act on the telephone. If the re-coupling were not present to effect the reinforcing action, these currents would be scarcely perceptible in the telephone 21; but owing to the re-

coupling, not only the high frequency component, but also the audio-frequency component is substantially reinforced.

An adjustable condenser 28 is connected 5 in parallel with the transformer primary 26 and admits of the regulation of energy received by the telephone from the circuit 9; the greater the capacity the smaller the current in the telephone, the most valuable 10 effect being determined by the relation between the incoming oscillations and that of the circuit, the adjustment of the condenser having the same influence as a variable coupling between the receiving oscillatory circuit and the detector circuit in 15 former systems of connection. Where the telephone winding 26 is in parallel with the re-coupling coil 12, as shown in Fig. 5, an equivalent regulation is obtained by variable inductance 28^a connected in series with 20 the coil 26.

The system shown and described with reference to Figs. 2 and 3 can be adjusted to produce continuous local oscillations in circuit 15, when the coupling between the circuits 15 and 7 of Fig. 2, or 15 and 9 of Fig. 25 3, is made close enough. The arrangement can then be used for receiving undamped oscillations by the beat or heterodyne 30 method described in the introduction to this specification.

The energy which may be produced by the arrangement described may attain a considerable value so that it is well adapted for 35 use for sending in wireless telegraphy.

The reinforced connection may be used for receiving very weak currents, by the production of tone by bringing the received oscillations into interference with the oscillations produced in the receiving circuit in 40 the way above described, and referred to in our statement of invention, in the so-called beat or heterodyne method.

Fig. 6 shows a system of connections arranged for this purpose. The oscillations taken up by the aerial 13 are supplied to a tuned intermediate circuit 37 by the coils 14 and 38 and by the circuit through the coils 39 and 16 to the detector circuit. The intermediate circuit and the detector circuit are linked by a coil 43 with a repeating circuit 41, coupling these two circuits, 37 and the detector circuit, by the coils 42 and 40 with the relay system.

The closed oscillatory circuit 31 of the energizing connection transmits its oscillations to the detector circuit, in which both sets of oscillations act. If the oscillatory circuit 31 is properly tuned so that the oscillations produced therein differ, by say about 1000 per second, from those received, then certain oscillations of this period are generated which act as a rectified impulse current and are perceptible in the telephone 21;

thus, by reason of the great constancy of 65 oscillations produced by the relay, one perceives a very pure tone in the telephone. While this is being produced, however, a considerable reinforcement takes place because the amplitude of the oscillations produced by the relay is made materially larger than that of the incoming wave, the action of the telephone corresponding to $(J_1 + J_2)^2$ 70 where J_1 and J_2 are the interfering currents. In this system, if the relay is fed with alternating currents in order to obtain pure tone, it is preferable to select low periodicity for 75 this current, so that a number of surges is present in each alternation.

The arrangement just indicated allows of 80 the reception of very weak signals from very remote stations which are otherwise scarcely perceptible. Where the incoming signals are sufficiently distinct to be received audibly, this system permits of a selectivity 85 over atmospheric and other disturbances. It is only necessary to make the receiving connection between the coils 14 and 38 very loose, which is well understood, or to increase greatly the aerial damping, in order 90 to cause the disturbing waves, which are themselves damped, to become less apparent. While the incoming signal trains are thus weakened, these are reinforced by the interference action, as pointed out, and the disturbing currents are not reinforced to the 95 same extent.

Our tests of this receiving action have shown that readily audible tone can be produced when the two oscillations are not even 100 approximately the same, but differ considerably from one another. This is noticeably the case when the oscillations at the receiving station are tuned to approximately an over-tone or a sub-tone of the received oscillations, and thus differ by a multiple or sub-multiple from them; this is particularly 105 advantageous in receiving damped oscillations produced by a spark.

This interference connection just described can also be employed several times in concatenation by causing interference oscillations first produced to co-act with a second producer of oscillations generating a current of different frequency, whereupon 110 the oscillations again interfere. In this manner, it is possible to obviate disturbances in receiving caused by atmospheric discharges or the like.

The property of the recoupled relay for 115 producing permanent oscillations in a system connected with it can be used when no special detector is provided (as in Fig. 5) for establishing an interference reception of a special kind, which enables the signals of a 120 damped or undamped sender to be reinforced to a high degree; and the arrangement for effecting this is illustrated in Fig.

7, where we employ also the energizing connection of the relay shown in Fig. 6. Aerial 13 is directly connected by coils 14 and 40 with the closed oscillatory circuit 31. The 5 telephone 21 is connected with the circuit 9, which carries the reinforced oscillations, by the means of the transformer 26, 27, as in Fig. 5. If the coupling between the coils 30 and 8, (by which the primary circuit of the 10 relay is connected to the circuit 31) is made close enough, the relay acts as above described as a generator, and produces in the circuit 31 oscillations of a frequency which comes into interference with that of the received 15 oscillations, the latter being simultaneously strengthened by the relay. The primary winding 26 of the transformer and the parallel adjustable condenser 28 form an oscillatory circuit, the frequency of which 20 is varied by the adjustment of the condenser, and in this circuit natural oscillations are likewise excited by the relay, so that if it be adjusted to a frequency which corresponds to an audible tone, this is continuously 25 heard in the telephone. If the adjustments are so regulated that the interference tone caused by the incoming waves is equal to the permanent tone in the oscillatory circuit 26, 28, whenever a signal arrives, the strength 30 of the tone will be varied; but if the interference tone is made somewhat different from the permanent tone by regulating the frequency in the circuit 31, the interference tone will then vary the pitch of the permanent 35 tone each time, rendering the signals perceptible. Owing to the mode of operation of this connection, a very exceptional reinforcement of the acoustic action takes place, so that the tone can be heard throughout 40 the room. The difference between the permanent tone and the tone which is varied when the waves arrive can be increased when the sender is put out of tune by depressing the key; that is, when a different wave is 45 sent in the intervals between sending from that sent when sending the signals, the interference tone acting on the permanent current being thereby changed. It is also possible in this manner of receiving by interference 50 to make the permanent tone no longer perceptible when listening for signals; for example, the telephone may be connected with an acoustic or electric resonator which is tuned only to the signal tone, so that only this tone can be distinctly heard 55 in the telephone.

Where we use in the claims the terms "converting" and "indicating" means, we mean to express any suitable means known 60 in the art by which alternating currents such as described are converted or rendered perceptible.

We claim as our invention:

1. In an arrangement for amplifying high 65 frequency alternating current impulses, the

combination with an aperiodic amplifying relay having a primary and a secondary path, means for conducting the weak high frequency impulses through the primary path thereof, a receiving circuit and means 70 for conducting the amplified high frequency impulses received at the secondary path to said receiving circuit, means associated with said receiving circuit for converting said high frequency impulses into and indicating 75 them as low frequency impulses; of means for returning the amplified high frequency impulses to said primary path before they are conducted to said converting and indicating means. 80

2. In an arrangement for amplifying high frequency alternating current impulses, the combination with a relay having a gaseous primary and secondary path, ionized by an incandescent cathode, means for conducting 85 the weak high frequency impulses through said primary path, a receiving circuit and means for conducting the amplified high frequency impulses received at the secondary path to said receiving circuit, means associated with said receiving circuit for converting said high frequency impulses into and indicating them as low frequency impulses; of means for returning the amplified high frequency impulses to said primary 90 path before they are conducted to said converting and indicating means. 95

3. In an arrangement for amplifying high frequency alternating current impulses, the combination with a cathode radiating tube 100 having an incandescent cathode, an anode and an auxiliary anode between the two latter, the path between the cathode and the auxiliary anode forming the primary path, the path between the cathode and the anode 105 forming the secondary path of the relay, a receiving circuit and means for conducting the amplified high frequency impulses received at the secondary path to said receiving circuit, means associated with said receiving circuit for converting said high frequency impulses into and indicating them as low frequency impulses; of means for returning the amplified high frequency impulses to said primary path before they are 110 conducted to said converting and indicating means. 115

4. An arrangement for receiving high frequency electrical oscillations comprising an antenna circuit, means for amplifying the 120 received oscillations and means for converting same into and indicating same as low frequency oscillations, said amplifying means consisting of an aperiodic relay having an ionized primary and secondary gaseous path, the primary path being suitably connected to said antenna circuit, the secondary path being connected with circuits which directly receive the amplified high frequency oscillations, said latter circuits being 125 130

coupled with the circuits intermediate the antenna circuit and the primary path, to return the amplified high frequency oscillations thereto, said converting and indicating

5 means being operatively connected to one of said circuits.

5. An arrangement for receiving high frequency electrical oscillations comprising an antenna circuit, means for amplifying the 10 received oscillations and means for converting same into and indicating same as low frequency oscillations, said amplifying means consisting of an aperiodic relay having an ionized primary and secondary gaseous path, 15 the primary path being suitably connected with said antenna circuit, the secondary path with circuits which directly receive the amplified high frequency oscillations, said latter circuits being coupled with the circuits intermediate the antenna circuits and the primary path, to return the amplified high frequency oscillations thereto, said converting and indicating means being operatively connected to one of said circuits which 20 conducts amplified high frequency oscillations.

6. An arrangement for receiving electrical high frequency oscillations comprising an antenna circuit, means for amplifying the 25 received oscillations and means for converting same into and indicating same as low frequency oscillations, said amplifying means consisting of an aperiodic relay having an ionized primary and secondary gaseous path, the primary path being suitably connected with said antenna circuit, the secondary path being connected with circuits which directly receive the amplified high frequency oscillations, 30 said latter circuits being coupled with the circuits intermediate the antenna circuit and the primary path to return the amplified oscillations thereto, said converting and indicating means being operatively connected to one of said circuits which 35 conducts amplified high frequency oscillations.

40 said latter circuits being coupled with the circuits intermediate the antenna circuit and the primary path to return the amplified high frequency oscillations thereto, and a

transformer for coupling said converting and indicating means with one of said circuits which conducts amplified high frequency oscillations. 45

7. An arrangement for receiving electrical oscillations, comprising an antenna circuit, means for amplifying the received oscillations and means for indicating same, said amplifying means consisting of an aperiodic relay having an ionized primary and secondary gaseous path, the primary path being suitably connected with said antenna circuit, the secondary path being connected with circuits which directly receive the amplified oscillations, said latter circuits being coupled with the circuits intermediate the antenna circuit and the primary path to return the amplified oscillations thereto, and a transformer for coupling said indicating means with one of said circuits which conducts amplified oscillations, and means, comprising an alternating current resistance created in the primary circuit of said transformer for controlling the amount of energy to be received by said indicating means. 50

8. An arrangement for receiving high-frequency oscillations comprising an electric circuit, means for altering the received high frequency current, a cathode relay for producing locally an alternating current of frequency different from that received, a grid included in said cathode relay, a circuit supplying the locally produced alternating current to the grid of the relay, and an indicating instrument. 55

In testimony whereof we affix our signatures in the presence of two witnesses.
